UNITED STATES PATENT OFFICE.

JOHN K. GOODRICH, OF ATLANTA, GEORGIA, ASSIGNOR TO ROBERT A. GRANT, OF ATLANTA, GEORGIA.

DESIGN FOR A VENDING-MACHINE CASING.

49,539.

Specification for Design.

Patented Aug. 22, 1916.

Application filed May 8, 1916. Serial No. 96,244. Term of patent 7 years.

To all whom it may concern:

Be it known that I, JOHN K. GOODRICH, a citizen of the United States, residing at Atlanta, in the county of Fulton and State of Georgia, have invented a new, original, and ornamental Design for a Vending-Machine Casing, of which the following is a specification, reference being had to the accompanying drawing, forming a part thereof.

The figure is a perspective view of a vending machine showing my design.

I claim:

The ornamental design for a vending machine casing as shown.

JOHN K. GOODRICH.
